UNITED STATES PATENT OFFICE.

ENRICO ROSENZI, OF PITTSBURG, PENNSYLVANIA, ASSIGNOR OF ONE-FOURTH OF HIS RIGHT TO T. J. MALONEY, OF SAME PLACE.

BLOW-PIPE FOR BLOWING GLASS.

SPECIFICATION forming part of Letters Patent No. 233,550, dated October 19, 1880.

Application filed July 12, 1880. (No model.)

To all whom it may concern:

Be it known that I, ENRICO ROSENZI, of Pittsburgh, in the county of Allegheny and State of Pennsylvania, have invented certain new and useful Improvements in Blow-Pipes for Blowing Glass; and I do hereby declare the following to be full, clear, and exact description of the invention, such as will enable others skilled in the art to which it pertains to make and use it, reference being had to the accompanying drawings, which form part of this specification.

My invention relates to an improvement in blow-pipes for blowing glass; and it consists in making the bulb at the end of the blow-pipe by which the glass to be blown is lifted from the mass in the oven separate, and of a different material from that of the pipe.

Heretofore it has been customary to make the blow-pipes for blowing glass in one piece of soft iron, the pipe or tube being united with the bulb. The bulb or enlarged end of the pipe is used for lifting a portion of the molten glass from the oven to be blown into shape or molded. When this is accomplished the glass, having cooled during the process and become brittle, is knocked off from the bulb.

When brought in contact with the hot glass the iron bulb becomes heated and oxidized, and oxygen emitted by the iron combines with the hot glass, imparting to it a greenish tint or film that destroys its transparency to some extent. Thus, although the glass when first melted may be colorless, as soon as it is taken from the oven to be blown it loses its clearness more or less from its contact with the iron bulb. Moreover, when the blown glass with its greenish film is knocked off from the bulb small fragments fall to the ground, and these shattered pieces are gathered to be remelted with the new material; consequently the new material already partakes, to some extent, of the green tint before it is lifted from the oven to be blown into shape.

To avoid the oxidizing and consequent staining of the glass I separate the bulb from the pipe and make it of a different material, as described hereinafter.

The accompanying drawings represent my invention.

Figure 1 shows a blow-pipe as now in use. Fig. 2 represents the pipe without the bulb. Fig. 3 represents the bulb detached from the pipe.

The form of the pipe differs from the old blow-pipes in being cut off from the bulb at a suitable length, and provided at that end with a screw that is to enter into the bulb to form a connection. The bulb is in the shape of a pear, and has in its tapering end a mother-screw for the reception of the screw on the pipe. The two parts when connected are made tight, so that the air blown into the pipe cannot escape but through the hole passing longitudinally through the bulb.

I make the bulb of fire-clay, gypsum, or any other material capable of resisting a high degree of heat without oxidation when brought in contact with hot glass. The material employed is, by mixing it with fluids, reduced to a plastic pulp and then molded into the proper form and dried. The fluid I use in making the pulp consists of five pounds of Glauber's salt, one-half pound of alum, and twelve pints of water to every one thousand pounds of clay, and hardens the clay or gypsum and imparts tenacity to it. The Glauber's salt neutralizes all uncombined oxygen contained in the gypsum, so that the gypsum is practically free of all uncombined oxygen while used in this connection. When sufficiently dry and hardened the iron pipe is screwed into the bulb, and when the latter is worn out or becomes broken a new one is readily put in place of the old one.

Although the described separation of the bulb from the pipe is to be preferred, the bulb of the blow-pipe now in use may be dipped into a mixture of the aforesaid materials made of a thickness to adhere and form a covering to the bulb sufficient to prevent a contact of the iron with the glass. A covering of this kind may be readily knocked off and renewed when required, and the blow-pipes now in general use be retained. It would be necessary to put a plug into the opening of the bulb to prevent its becoming filled by the mixture of clay, gypsum, or other substances forming the covering, which plug is only to be removed when the temporary coating has become dry. The blow-pipe may also be made in one piece of

the same material with the bulb hereinbefore described, the same fluid for hardening the pulp being added and mixed with it.

Having thus described my invention, I claim—

- 5 1. A blow-pipe for blowing glass, composed of two pieces, a pipe and a pear-shaped bulb, of different material, substantially as described.
- 10 2. A blow-pipe for blowing glass, composed of two pieces, a pipe and a bulb, screwed together, the latter being made of fire-clay, gypsum, or other kindred material free from uncombined oxygen and capable of resisting a high degree of heat, substantially as described.
- 15 3. A blow-pipe for blowing glass, composed entirely of fire-clay, gypsum, or other material free from uncombined oxygen and capable of

resisting a high degree of heat, substantially as described.

4. A covering or surrounding for the bulb 20 of a blow-pipe for blowing glass, consisting of a mixture of fire-clay, gypsum, or other material, with a fluid which neutralizes the uncombined oxygen in the gypsum and hardens the clayey mixture and prevents the oxidizing of glass, 25 substantially as described.

In testimony that I claim the foregoing I have hereunto set my hand this 26th day of June, 1880.

ENRICO ROSENZI.
